MAGNETIC CONTROL DEVICE

Gerhard H. Dewitz, Westport, Conn., assignor to C. G. S. Laboratories, Inc., Stamford, Conn., a corporation of Connecticut

Application September 18, 1952, Serial No. 310,341

10 Claims. (Cl. 336—155)

This invention is in the field of high frequency saturable core magnetic apparatus in which the inductance of a signal winding is controlled electrically by varying the magnitude of a current sent through a control winding.

In such controllable inductors, sometimes called saturable reactors, the control and signal windings are wound on a common ferromagnetic core. Variation in the current flowing thru the control winding changes the degree of magnetic saturation of the core and so varies the effective inductance of the signal winding. Thus, the magnitude of an alternating current passed through the signal winding can be controlled in accordance with variations produced in the unidirectional control current flowing through the control winding.

Such devices have been used largely for low frequency applications: their high losses and slow response time have prevented higher frequency applications.

The development of ferromagnetic ceramic core materials, as described by Snoeck in U.S. Patents 2,452,529; 2,452,530; and 2,452,531, has permitted higher frequency operation. Controllable inductors using such ceramic materials are described in my copending applications Serial Nos. 213,548 and 278,069 filed March 2, 1951 and March 22, 1952, respectively. The latter has now issued as Patent No. 2,820,109 dated January 14, 1958. Those devices are provided with ring cores having a rectangular opening or hole through the rim through which two portions of the signal winding, are wound. An alternating signal current to be controlled is passed through these two portions of the signal winding in such manner as to produce signal flux lines encircling this opening. This application is a continuation-in-part of both of these earlier applications.

By means of the present invention the upper frequency limit of controllable inductors is still further extended, the control current is rendered more effective, and the isolation of the control and signal winding is further improved.

In connection with one aspect of the invention, the magnetic saturation of the flux path of the signal winding is maintained substantially uniform throughout its length. This is important because the signal flux tends to spread into those portions of the core having lower saturation and therefore higher effective permeability. Generally speaking, the losses in ferromagnetic ceramic material are higher when the magnetic saturation is low: accordingly, any core areas of low saturation represent areas having increased losses. If the signal winding is used in a resonant circuit, maximum saturation of the core occurs at the highest frequencies: accordingly, any portion of the flux path of the signal winding that is at low saturation increases the losses at these higher frequencies, reducing the Q of the signal winding and reducing the upper frequency limit.

The cores are formed with reduced cross sectional areas adjacent both sides of the signal winding opening or

2

openings in order to provide pre-saturation or magnetic isolation regions at these locations. These isolation regions act to restrict and direct the path of the control saturation flux so as to cause it to pass through substantially the entire core material closely adjacent the opening. Thus the saturation flux has a maximum effectiveness in relation to the closed path of the signal winding flux passing around this opening. Moreover, these pre-saturation regions act to confine the signal winding flux to these same portions of the core, whereby when the control flux is at its maximum saturation value, the signal flux is confined to portions of the core which are substantially fully saturated.

I have found that by forming the core in this manner, the effective value of the Q of the ferromagnetic ceramic material used is raised at high frequencies so that magnetic apparatus made according to my invention can be used at frequencies hitherto unobtainable in such apparatus using ferromagnetic core material. For example, with my invention the upper frequency limit of ferromagnetic ceramic materials is increased many fold.

Irrespective of whether the cores are composed of ceramic material, some improvements are experienced by using this invention with other core materials having somewhat similar magnetic characteristics. For example, the action of the control current is rendered more effective and the isolation of the signal windings from the control windings is increased.

These and other objects, aspects, and advantages of the present invention will be in part pointed out and in part apparent from the accompanying drawings, in which:

Figure 1 of the accompanying drawings shows a controllable inductor embodying the present invention;

Figure 2 is an enlarged partial elevational view of the signal winding core portion and adjacent portions of the core of the inductor of Figure 1 with the windings omitted to show the relationships more clearly;

Other core forms are illustrated in the partial elevational views of the signal winding portions and neighboring portions of cores shown in Figures 3 to 7 in which the windings have been omitted from the cores in order to illustrate more clearly the differences therebetween.

Figure 3 is a view of a rectangular signal winding core portion with rectangular flux control notches adjacent the opening;

Figure 4 shows the reduced cross-sectional area or flux control region extending a relatively large distance on either side of the signal winding hole;

Figure 5 shows another core form with staggered indentations adjacent the signal winding hole;

Figure 6 shows still another form of the region of flux control reduced cross sectional area, the core being formed from two pieces fitted together along its center line; and

Figure 7 illustrates more than one signal winding portion formed on the same core.

The inductor, generally indicated at 2, in Figure 1, includes a ring core 4 having a form similar to that shown in Figure 9 of my copending application, Serial No. 278,069, now Patent No. 2,820,109, as mentioned above. This core is composed of a ferromagnetic ceramic material as described above or core materials having somewhat similar magnetic characteristics. I have found that these ceramic materials offer marked advantages because of their high effective Q's, their high initial permeability, their relatively low saturation threshold and wide operating range, etc. Moreover, these materials apparently exhibit the property discussed above that within a range at high frequencies their losses decrease with increase in magnetic saturation.

The ring core 4 has a first portion of substantially uniform cross sectional area around which is located the con-

trol winding 6, usually having a relatively large number of turns. However (see Figure 2), between the broken lines 7 and 8, is located the signal winding core portion in which by following the core from the region of either the line 7 or 8 toward the center of a signal winding opening 9 it is seen that the cross sectional area of the core is first gradually and then progressively more abruptly decreased by means of pairs of curved indentations 10A and B, and 11A and B. These curved indentations form two throats or flux control regions, generally indicated at 12 and 14, near both sides of the transverse signal winding opening 9, which accommodates the signal winding, generally indicated at 18 (see Figure 1).

The control winding 6 is connected to a suitable source of control current diagrammatically indicated at 20, and the degree of magnetic saturation of the entire core is controlled by the current flowing through winding 6 in a manner well known in the art of saturable core magnetic apparatus. The control flux produced thereby flows in a closed path through the core 4, for instance, it may flow through the signal winding portion in the direction of the arrows 22 shown in Figure 2.

In order to reduce the undesired magnetic coupling between the control winding 6 and the signal winding 18, the latter is formed into two equal sections 18-1 and 18-2. These sections are wound through the transverse hole 9 and around spaced rim or branch portions 24 and 26 of the core 4, which pass around opposite sides of the hole 9. The sections 18-1 and 18-2 are connected in series in such a direction that signal flux lines formed by current flowing from the controlled circuits, diagrammatically indicated at 28, through the winding 18 travel in a closed path around this hole, passing through the lengths of core branches 24 and 26.

In order to confine the path of the saturation flux 22 and to direct it along the lengths of the core branches 24 and 26 so that it regulates with maximum efficiency the saturation of substantially all portions of the magnetic material adjacent the hole 9, I provide the pairs of indentations 10A and B and 11A and B to form the narrow flux control throats or presaturation regions 12 and 14 of relatively abruptly reduced cross sectional area closely adjacent each end of the hole 9.

These pairs of indentations are symmetrically formed to left and right of the center of the opening 9, and they are similar above and below the longitudinal central axis of the core. Each indentation is formed with curved side walls, which as seen in Figure 2 conform to a circular arc over a substantial portion of their length. For instance, the depression 10A has a convex arcuate side beginning at the dotted line 7 and extending down toward the throated region 12, where it merges with the bottom of the depression which is rounded with a concave curve. The resulting general pattern of the saturation flux around the hole 9 is indicated by the arrows 22. As mentioned above, the alternating signal flux caused by the high frequency signal currents flowing in the winding 18, passes in a closed path around this hole and is regulated by the magnitude of the control flux 22. The action of these presaturation throat regions 12 and 14 in confining the saturation flux 22 and, moreover, in providing additional isolation of the signal winding 18 from the control winding 6 is explained below.

During operation, the current through the control winding 6 is varied in order to vary the inductance of the signal winding 18. When the control current is very small, the portions of the core 4 surrounding the hole 9 have a low control flux density, so that their permeability to the alternating signal flux is high. Hence, the inductance of the winding 18 is large. As the control flux 22 is increased, the degree of saturation of the signal flux path around the hole is increased, thus decreasing the permeability of this path and hence decreasing the inductance of the winding 18. At maximum value of the control flux 22, substantially the entire signal flux path around the hole 9 is

fully saturated, and the inductance of the winding 18 is at a minimum.

The tendency of the signal flux is to spread out away from the hole and pass through those regions of lowest reluctance or highest permeability neighboring thereto. That is, in the absence of the restricted pre-saturation throat regions 12 and 14, the signal flux would tend to loop out on each side of the hole 9 toward the dotted lines 7 and 8 for these portions of the core 4 have lower average values of saturating flux than most regions of the core adjacent the hole. Thus, in the absence of restrictions 12 and 14, as the signal flux path is further and further saturated, the signal flux would have a greater and greater tendency to spread away from the desired path around the hole 9. The result of this tendency of the signal flux to pass into regions of lower saturation, which occurs in variable inductors as they are now known in the art, is to prevent the maximum control of the signal flux by the areas saturated by the control flux. The presence of the presaturation regions 12 and 14 restricts the control flux 22 to a relatively small cross sectional area at these locations. Hence, as the control flux increases, the pre-saturation areas are among the first areas to approach the threshold of saturation, and consequently their permeability is forced down, confining the signal flux to the core material in the branches 24 and 26 and at each end to material adjacent the hole. Thus, the signal flux is isolated from portions of the core carrying the control winding 6 and travels a closed path closely adjacent the hole where it is very effectively controlled by the flux 22, to produce a low value of minimum inductance.

In addition to providing isolation and highly effective control action, the pre-saturation regions 12 and 14 force the signal flux to traverse core material, which, in the low inductance range (which is often the high frequency range), is substantially all fully saturated. It is a characteristic of this ceramic material that in this high frequency range the losses in the material decrease with increasing magnetic saturation. That is, within certain ranges losses are a direct function of permeability. In cores embodying the present invention the signal flux is forced to travel in low loss areas of high saturation, as the inductance of the signal winding is decreased, thus providing extremely high Q, high frequency operation.

The relationships between the pre-saturation throats or isolation areas 12 and 14 and the dimensions of the branches 24 and 26 as they affect the operation of the unit 2 are as follows. I have found that for many applications it is preferable to have the cross sectional areas at 12 and at 14 each slightly less than the sum of the cross sectional areas of the branches 24 and 26. For example, the cross-sectional area at A is usually around 80 to 90% of this sum. Also, the maximum width of the core near the signal winding opening is considerably greater than the width of the throats 12 and 14.

A further reduction in the cross-sectional areas of the pre-saturation regions provides an even greater isolation effect, which may be desirable in some applications, where the added reluctance in the control circuit is acceptable. When the areas of the pre-saturation regions are increased from this 80 to 90% value, the reluctance of the control circuit is decreased so that less control current is required; however, there is some loss in effective Q. For example, I have found that for lower frequency operation, and in certain variable frequency oscillator applications, lower Q values are acceptable.

In Figure 3 is shown another embodiment of the present invention in which the core 30 is provided with a rectangular opening 32 and a pair of straight-sided slots near each end thereof to provide pre-saturation or isolation regions or throats 34 and 35. An advantage of this form of core is that a relatively larger opening 32 is available to receive the signal winding without any increase in the overall core dimensions. With this form it is preferable to have the cross-sectional area of each

of the throats 34 and 35 approximately equal to the sum of the cross-sectional areas of each of the branches 36 and 37.

It should be noted that the form of signal winding core portion shown in Figures 2, 5, 6, and 7 has a transition range in the pre-saturation region wherein the rate of reduction of cross sectional area of the core as seen by progressing along the core toward the center of the signal winding opening is more or less first gradual and then becomes more abrupt. For example, in Figure 2 it is seen, by following the core from the dotted line 7 toward the opening 9, that there is a transition range in which the cross sectional area is more or less gradually reducing, and then it more abruptly reduces to the narrowest portion of the throat 12. Although the form shown in Figure 3 is satisfactory for many applications, I prefer the use of a transitional range as yielding a higher effective Q in the higher frequency ranges.

In Figure 4 is shown in elevation a portion of a ring core 38 with a small annular signal winding core 39 formed integral therewith and having branches 40 and 41 surrounding the hole 42. In this embodiment the main core 38 has regions 44 and 46 of reduced uniform cross sectional area which extend all the way around the core 38. Also, the cross sectional area of the core 38 may be increased a portion of the way around in order to reduce the reluctance of the control flux path. Because the regions of reduced cross sectional area extend for considerable distances on either side of the hole 42, they provide extensive presaturation throats of a width which is considerably less than the maximum width measured across the annular core portion 40. The cross sectional area of the main ring core 38 in regions 44 and 46 may be approximately equal to the sum of the cross sectional areas of the branches 40 and 41, thus being somewhat wider than the throat regions in other figures of the drawings.

In Figure 5 is shown a ring core 48 having a signal winding hole 49 with a pair of curved single indentations 50 and 51 on each side thereof. By progressing along the core 48 from either side toward the hole 49, it is seen that there is first a gradual and then an abrupt reduction in the cross sectional area of the core 48 on each side of the hole 49 to form the pre-saturation regions, generally indicated at 52 and 54. An advantage of this form of core is that the number of indentations is reduced, while their staggered symmetrical relationship equalizes the reluctance of the magnetic circuits through the core material 48 and along the two sides of the hole 50.

The core shown in Figure 6 is similar to the core shown in Figure 4 of my co-pending application, Ser. No. 213,548, mentioned above. It comprises a first core portion 56 of relatively large and uniform cross section for receiving the control winding, and providing a low reluctance path for the control flux. Between the dotted lines 58 and 60 the core tapers to a smaller cross sectional area and then abruptly reduces at the pairs of notches 62A and B and 64A and B adjacent a signal winding hole 66. Each of these tapering regions and these notches provides an isolation or pre-saturation region adjacent the hole 66, generally indicated at 68 and 70, respectively. Two branches 72 and 74 pass by either side of the hole 66. The maximum distance across the core adjacent the hole 66 is significantly less than the width of the first portion 56. On the branches 72 and 74 the two portions of the signal winding are placed. Since with this configuration the cross sectional area of the first core portion 56 can be relatively greater for a given size of signal winding, the reluctance to the control flux is considerably reduced, while at the same time an effective control action is obtained.

In order to facilitate in the fabrication, the core may be formed from two sections which are mirror symmetrical and placed together along the center parting line 76.

This core may also be formed from a single integral core piece.

The partial elevational view of the core 78 in Figure 7 shows two spaced signal winding openings 80 and 82. Adjacent each of these openings are pairs of valley-shaped indentations 84A and B and 86A and B, and 88A and B and 90A and B, respectively, which are similar to those used in forming the core 4, as shown in Figure 2. Each of these indentations is curved and has a gradually increasing slope toward its center to form pre-saturation and isolation regions adjacent each side of the openings 80 and 82. Thus, with the use of the principles shown in the core 78 a single control winding can be used to control the inductance of two, or more, signal windings, and because of the formation of the pre-saturation and isolation regions, each of these inductances is substantially entirely independent of the other controlled windings on the same core and has no undesired mutual coupling with the control winding.

Although only one or two signal winding openings are shown, it is understood that by using the principles of this invention a larger number of independent controlled inductances capable of high effective Q, high frequency operation can be utilized on one ring core.

It is to be understood that the principles set forth above in connection with single ring cores apply equally well to multiple ring core structures using two or more cores.

From the above description it will be apparent that the saturable core magnetic units embodying the present invention are well adapted to attain the ends and objects set forth herein and that the various embodiments of the invention shown herein can be modified so as to produce operating characteristics best suited to the needs of each particular use.

I claim:

1. A core of ferromagnetic material having a first closed magnetic path therein and a transverse opening therein dividing said first magnetic path into first and second spaced magnetic branches passing on either side of said transverse opening and forming a second closed magnetic path passing around said opening, said core having a pair of throat portions of reduced cross sectional area adjacent to opposite sides of said transverse opening, said throat portions each having a smaller cross-section than the total cross-section measured directly across said first and second spaced branches and said throat portions each having a significantly smaller width than the maximum width of said core as measured directly across said first and second spaced branches.

2. A core of ferromagnetic material defining a first substantially closed flux path, said core having a first portion with a transverse opening therein dividing said first flux path into first and second spaced magnetic branches passing along opposite sides of said opening, said branches defining a second substantially closed flux path passing around said opening, said core having a pair of throat portions formed therein, said throat portions being adjacent to opposite sides of said first portion and being spaced a short distance from opposite ends of said transverse opening and each having a substantially less width than the maximum width of said core as measured directly across said first and second branches, the cross sectional area of each of said throat portions being approximately equal to the sum of the cross sectional areas of each of said separate branches.

3. A variable induction apparatus comprising magnetic core means having a first closed magnetic flux path therein, a first winding surrounding a portion of said core means and magnetically coupled to said first closed flux path, a transverse opening in said core means dividing said first closed path into first and second spaced branches passing on opposite sides of said opening and forming parallel branches in said first flux path, and a second winding having first and second portions wound through said opening and respectively around said spaced

branches, a second closed magnetic flux path for said second winding passing around said opening, said core means defining first and second pairs of opposed indentations near the opposite ends of each of said branches the minimum width of said core means at each pair of indentations being substantially less than the maximum width of said core means measured directly across said first and second spaced branches, the minimum cross sectional area of said core means at said pairs of indentations being not significantly greater than the sum of the minimum cross sectional areas of said first and second spaced branches, said pairs of indentations deflecting said first path at the opposite ends of said transverse opening so as to pass through substantially all portions of the core material adjacent said transverse opening whereby the degree of saturation along substantially all of said second closed flux path is effectively controlled and said second winding has a high effective Q at high operating frequencies.

4. A controllable inductance apparatus comprising magnetic core means defining a first closed magnetic flux path therein, a first winding surrounding a portion of said core means arranged to induce magnetic flux in said first closed path, a transverse opening in said core means dividing said first path into first and second spaced branches passing on opposite sides of said opening and defining a second closed magnetic flux path passing around said transverse opening and through said first and second spaced branches, a second winding having first and second portions wound through said opening and respectively around said spaced branches, said core means including a pair of pre-saturation regions of abrupt reduction in width near opposite ends of said branches, said pre-saturation regions having a minimum width substantially smaller than the maximum width measured directly across said first and second spaced branches, said core means in said pre-saturation regions having a cross sectional area less than the sum of the cross sectional areas of said first and second spaced branches, said pre-saturation regions causing said first flux path to deflect inwardly adjacent to opposite ends of said transverse opening so as to travel substantially the entire way around said transverse opening, and a transition region included in said core means adjacent each of said pre-saturation regions, the cross sectional area of the core means relatively gradually and progressively decreasing in said transition region in a direction toward said pre-saturation region, said transition regions being spaced further from said transverse opening than said pre-saturation regions.

5. A controllable inductance apparatus as claimed in claim 4 and wherein the cross sectional area of the core means in said pre-saturation regions is in the range from about 80% to about 90% of the sum of the cross sectional areas of said first and second spaced branches.

6. A controllable inductance apparatus comprising core means of ferromagnetic material having a first portion of approximately uniform cross sectional area and a second portion with a small transverse opening therein defining a pair of spaced branch portions passing around opposite sides of said opening each of said branch portions having a substantially equivalent cross sectional area, said first and second core portions defining a closed path for magnetic flux, and defining a large opening with said closed path passing around said opening and through said first and second core portions, a first winding passing through said large opening and around said first portion and a second winding having first and second portions wound through said transverse opening and respectively around said opposite branch portions, said core means defining first and second opposed pairs of indentations therein near opposite ends of said transverse opening, the walls of each of said indentations over a major part of their length as seen in elevation being arcuate and convex, the minimum widths of said core means as measured at the narrowest points under said opposed pairs of

indentations near opposite ends of said transverse opening being substantially less than the maximum distance across said transverse opening between the outside surfaces of said respective branch portions, and the cross sectional areas of said core means as measured at the narrowest points under said opposed pairs of indentations being approximately equal to the sum of the cross sectional areas of said pair of spaced branch portions.

7. A core of ferromagnetic material having a first closed magnetic path therein and a rounded transverse opening therein dividing said first flux path into a pair of branch paths of substantially equivalent cross sectional area passing on opposite sides of said opening, said core forming a second closed magnetic path passing around said opening and through said branch paths, and a winding having first and second equal portions wound through said transverse opening and respectively around said opposite branch paths and serially connected in the same direction with respect to said second path, said core having indentations abruptly decreasing its cross sectional area adjacent opposite ends of said branch paths to an area less than the sum of the cross sectional areas of said branch paths, said indentations being spaced from said opening, said core having a substantially larger cross sectional area commencing at the extreme limits of said indentations and extending for substantial distances away from each of said indentations.

8. A variable inductance apparatus comprising a magnetic core having a first substantially closed flux path therein, a first winding surrounding said first path, a transverse opening in said core dividing said first path into first and second branches passing on opposite sides of said opening, a second winding having first and second portions wound through said circular opening and respectively around said branches, the cross sectional area of said core as it extends in a direction toward either side of said transverse opening first gradually and then abruptly decreasing to a minimum value of from 80% to 90% of the sum of the cross sectional areas of said branches.

9. Controllable inductance apparatus comprising magnetically permeable core means defining a first closed path for magnetic flux, a first winding on said core means passing around said first path, said core means including a transverse opening therein and dividing said first path into first and second spaced magnetic branches extending along opposite sides of said transverse opening and defining a second closed path for magnetic flux passing around said transverse opening and through said first and second spaced magnetic branches, a second winding having first and second parts passing through said transverse opening and around said first and second spaced magnetic branches, respectively, said parts of said second winding being interconnected in series aiding relationship with respect to the flux passing around said transverse opening, said core means having indentations near opposite ends of said transverse opening and adjacent to opposite ends of said spaced magnetic branches, the cross sectional areas of said core means measured at the bottom of said indentations and adjacent to the opposite ends of said spaced magnetic branches being less than the total cross sectional area as measured directly across said spaced magnetic branches and the widths of said core means measured at the bottom of said indentations and adjacent to opposite ends of said spaced magnetic branches being substantially less than the maximum overall width of said core means measured from the outside surface of said first magnetic branch to the outside surface of said second magnetic branch.

10. Controllable inductance apparatus comprising magnetically permeable core means defining a first closed path for magnetic flux, a first winding passing around said first path, said core means including a first portion having a transverse opening passing therethrough and dividing said first flux path into first and second spaced magnetic

branches passing on opposite sides of said opening, said first core portion defining a second substantially closed flux path passing around said opening and through said first and second spaced magnetic branches, a second winding having first and second parts passing through said transverse opening and respectively around said first and second spaced magnetic branches, said parts of said second winding being interconnected in the same sense with respect to flux passing around said transverse opening in said second path, said core means including a pair of throat portions in said first flux path and adjacent to opposite ends of said branches, each of said throat portions having a substantially smaller minimum width than the over-all width of said first core portion measured directly across from the outside of said first branch to the outside of said second branch, said throat portions each having a cross sectional area which is substantially equal to the

sum of the cross sectional areas of said first and second spaced magnetic branches, said throat portions converging the flux in said first path at opposite ends of said transverse opening, whereby the flux in said first path passes along substantially the entire length of said second path.
